UNITED STATES PATENT OFFICE.

NOYES F. PALMER, OF JAMAICA, NEW YORK.

TELEPHONE.

SPECIFICATION forming part of Letters Patent No. 353,755, dated December 7, 1886.

Application filed March 27, 1886. Serial No. 196,753. (No model.)

To all whom it may concern:

Be it known that I, NOYES F. PALMER, of Jamaica, Queens county, State of New York, have invented a new and Improved Telephone, 5 of which the following specification is a full, clear, and exact description.

This invention relates to an improved telephone transmitter or receiver combined for articulate speech or other sounds.

10 The invention consists in the combination of a telephone-transmitter with a spring-arm that carries a bar which is located between the diaphragm and the magnet, and which is provided with two springs carrying the electrodes.

15 The invention also consists in the various features of improvement hereinafter more fully pointed out.

In the accompanying drawings, Figure 1 is 20 a cross-section of a telephone provided with my improvement. Fig. 2 is a top view of the electrode, and Fig. 3 a section on line *x*, Fig. 2.

Upon one pole of a magnet is mounted a 25 spring-arm, A, extending over the opposite pole, so that it can be attracted by such opposite pole. To this arm A is attached a socket or extension bar, L, with screws *a*' *a*'. This bar has an upward extension, *r*, attached to the diaphragm D' by screw *d*. An extension, 30 L', on the lower end of bar L, is provided with an adjusting-screw, *l*', by which it is connected to a bracket, L'', the latter being suitably fastened to the case or frame. The rigidity of the bar L and diaphragm D' by this improved 35 method produces the most sensitive effects. This bar L is also provided with a slotted shoulder-piece, *l*'', to which are secured the ends of the electrode-springs, insulated from each other.

40 Into the slot of the shoulder *l*'' is placed an insulating substance, I, having a cavity, into which is placed the lower spring-arm, *s*'', of electrode E''. Over arm *s*'' is placed insulating materials *w*'' and *w*', the latter of a wedge 45 shape. Across the upper part of the shoulder *l*'' extends, through opposite apertures, a pin, *p*, having a split shank. Around this split shank is placed the bent end of the upper 50 spring-arm, *s*', of electrode E'. Thus this arm is securely bound in such manner as to permit its adjustment by turning the split pin *p* to

any desired pressure. The coil or tension to spring-arms *s*' can be so shaped by several turns, before placing in the split pin *p*, that the pressure can be reduced to a very fine degree, and 55 yet be in perfect regulation by turning the split pin *p*.

The advantages of this improved transmitter are as follows: First, it can be adjusted to any degree of pressure required with ease; 60 second, this adjustment is positive and permanent; third, the attachment of the bar to the diaphragm and case in a rigid manner produces the most sensitive results in the electrode-contacts; fourth, the simplicity of the 65 two electrodes and bar will permit a multiple number of points to be used in one transmitter, thus subdividing the current and rendering the most sensitive action.

I prefer to combine with one instrument two 70 diaphragms—to wit, the diaphragm D', already described, and a diaphragm, D. This latter diaphragm adapts the instrument to be used as a receiver, the diaphragm D' being used when the instrument is employed as a 75 transmitter. Two permanent magnets, B' B, are employed, one opposite each diaphragm. The magnets B' B are surrounded by helices G' G, that constitute part of the wire for the magneto-current. This current travels as follows: Starting from a distant station, it runs 80 over wire *m* to induction-coil K, to wire *m*', to helix G, to wire *m*'', to helix G', to wire *m*''', and thence to the ground, or to a farther station. The local battery-current runs from 85 electrode E' to wire *n*, to battery H, to wire *n*', to induction-coil K, to wire *n*'', and to electrode E''.

The operation of the apparatus is as follows: 90 The vibrations of diaphragm D' are transmitted by bar L to the electrodes E' E'', these vibrations producing corresponding variations of the battery-current. The variations of the battery-current produce corresponding variations in the strength of the magneto-current 95 through the induction-coil K. The variations in the magneto-current produce vibrations of the diaphragm at the distant station, as is well known.

The operation of this transmitter is such 100 that the sound-waves vibrate the diaphragm and the electrodes vibrate in harmony there-

with, and such electrode vibrations allow the variations in the current from battery and induction coil to affect the magnetic current in such manner as to increase the volume of each 5 magnet impulse, conforming in tone and pitch to the sound-waves against the diaphragm, as is common in this class of transmitters; but in this transmitter there is a different feature or improvement, resulting from the direct contact 10 of the electrode-bar with the diaphragm itself, which contact with the diaphragm continues the vibrations of the electrodes in unison with the diaphragm.

In the usual form of transmitter the electrodes receive their vibration by contact only 15 with the diaphragm. In this transmitter these vibrations are received from the rigid bar as well as from the diaphragm contact.

I claim as my invention—

- 20 1. The combination, in a telephone-transmitter, of spring-arm A, and bar L, having shoulder-piece ℓ , with springs $s' s^2$, carrying electrodes E' E², and secured to such shoulder-piece, substantially as specified.
- 25 2. The combination, in a telephone-transmitter, of spring-arm A, and bar L, having

extension L', and socket ℓ' , with springs $s' s^2$, carrying electrodes E' E², and with insulators I w², and split pin p, for holding and adjusting spring s', substantially as specified. 30

3. The combination, in a telephone-transmitter, of bar L, having shoulder-piece ℓ and extensions $\ell' L'$, with diaphragm D', and bracket L², the extension ℓ' being attached to diaphragm D', and the extension L' being attached to bracket L², substantially as specified. 35

4. The combination, in a telephone-transmitter, of a diaphragm with a bar attached to said diaphragm, said bar having one extension projecting away from said diaphragm, provided with an adjusting-screw operating into a bracket secured to the case or frame, and said bar having another extension about parallel with said diaphragm provided with a socket carrying two electrodes, one electrode 45 having a pivotal adjustment in said socket, substantially as specified.
